UNITED STATES PATENT OFFICE.

LINUS PORTER BURROWS, OF WASHINGTON, DISTRICT OF COLUMBIA,
ASSIGNOR TO BURROWS DEVELOPMENT COMPANY, OF WASHINGTON,
DISTRICT OF COLUMBIA, A CORPORATION OF MAINE.

APPARATUS FOR UTILIZING STEAM.

SPECIFICATION forming part of Letters Patent No. 740,085, dated September 29, 1903.

Application filed November 23, 1901. Serial No. 83,395. (No model.)

To all whom it may concern:

Be it known that I, LINUS PORTER BURROWS, a citizen of the United States, residing at Washington, in the District of Columbia, have invented new and useful Improvements 5 in Apparatus for Utilizing Steam, of which the following is a specification.

This apparatus for utilizing steam comprises an expansion and radiation chamber, 10 in which the steam is suddenly expanded to a larger volume and separated without material condensation from any water held in suspension, means for heating the steam to a high temperature, and means for burning 15 the gaseous products thereof in conjunction with other fuel.

My apparatus is fully shown in the accompanying drawings, in which—

Figure 1 is a front elevation. Fig. 2 is a 20 vertical longitudinal section on line II II of Fig. 1. Fig. 3 is a horizontal section on line III III of Fig. 1. Fig. 4 is a vertical transverse section on line IV IV of Fig. 3. Fig. 5 is a detail perspective view of the air-diffusing device and ash-receiver removed from 25 the fire-box.

High-pressure steam taken from the dome of a steam-boiler or other convenient source is brought through a considerable length of 30 pipe 1, having a control-valve 2, and by means of a pressure reducing and regulating valve 3 of any suitable construction is lowered in pressure to, say, from four to six pounds per square inch. It then enters the top of a vertical expansion and radiation cylinder 4, preferably of sheet metal. This cylinder has in its bottom a valved outlet 5 for withdrawing the water of condensation. From the side of this chamber a pipe 6, containing a valve 40 7, leads through the front wall of the fire-box just above the grate-bars and near the left-hand wall of the fire-chamber. On each side of the fire-chamber is located a vertical series of pipe-sections 8 9, alternately connected at 45 opposite ends to provide a zigzag passage. I have shown five superposed sections; but this number may be increased or diminished, according to circumstances. The lowermost section of pipe at the left hand of the fire-chamber is connected to inlet-pipe 6, and the steam passing up through the separate sec-

tions 8 is carried from the farther end of the top section transversely across the rear end of the fire-chamber to the corresponding top section of the right-hand series of pipe-sections 9. The resulting gas then passes from the lowermost section through the front wall of the fire-box to a coupling 10, having two outlets. From one of these outlets leads a valved pipe 11 to carry the gas to any desired 60 point of use. From the second outlet a pipe 12, containing a drip-cock 13, leads to a pressure-relief valve 14. From the pipe 12 extends a valved pipe 15, which is bent and passes through the front wall of the fire-box 65 at a point midway of and at the upper surface of the grate-bars. A T-coupling thence leads the gas to pipe 17 and burner 18 near the right hand of the fire-chamber and just above the grate-bars and through a similar 70 pipe 19 to a similar burner 20 at the left-hand side of the fire-chamber. The burners 18 20 each consist of a length of pipe closed at the farther end and having a longitudinal series of gas-passages in the upper and inner wall 75 in such position that the jets of flame issuing from them converge and meet at the upper middle portion of the fire-chamber.

Below the fire-grate is removably hung my improved air-diffusing and ash-receiving pan. 80 This pan consists of a rectangular cast-iron frame 21, corresponding in general outline to the grate-bar frame, and vertical sides 23 of finely-perforated sheet metal riveted at their lower edges to the outer side of the frame. 85 The pan is hung below the grate-bars by any suitable means, such as hooks 24, having upper bent ends carried by the grate-bars and lower bent ends entering openings near the four corners of the upper edge of the pan. 90 The pan can be entirely removed by disengaging the lower ends of the hooks from the openings in the pan, and the hooks can be detached from the grate-bars by turning them until the upper bent ends are parallel to the 95 slots through the grate-bars. The pan-frame 21 has a central longitudinal bar 22, provided with longitudinal rabbets 25. The two parallel rectangular openings thus provided each contain an ash receiving and dumping plate 100 26. These plates are supported at the front and rear ends by trunnions 27 28, secured to

the ends midway of the width of the plates and resting in recesses in the pan-frame. The trunnions at the front extend through the furnace-wall and are provided with handles, by which the plates 26 can be rotated to a vertical position to discharge ashes into the ash-pit below. The adjacent edges of these plates normally lie in the rabbets 25 of the center bar 22. These adjacent portions of 5 plates 26 rotate upward and outward toward the sides of the pan in dumping and are returned to their normal position by any suitable counterweights, those shown being iron rods secured to the lower edge of each plate 10 by staples riveted through the plate. The finely-perforated sides of the pan cause the entering air to be uniformly distributed beneath the grate-bars, the amount of air supplied being regulated as desired not only by 15 the ash-pit door 29, but by closing a suitable number of the perforations in the pan sides with clay.

The operation of the gas-producing apparatus is as follows: Water converted into 20 high-pressure steam and brought to the furnace by pipe 1 is reduced in pressure by valve 3, from which it enters chamber 4, having pressure-gage 44. The rapid expansion of steam in this chamber causes its temperature 25 to fall until a portion is condensed into water, which is drawn off at the bottom by cock 5. The expanded and dried steam then passes to the gas-generator proper, consisting of the described convolutions of pipe 8 9, so arranged 30 within the fire-box as to be subjected not only to the direct heat of any fuel in combustion on the grate, but also to the heat radiated by the adjacent brick side walls of the fire-chamber. The steam is thus converted 35 into a gas of high calorific and illuminating power, which may be carried off through pipe 11 and used for digesting solid substances and various other purposes. That portion of the gas carried by pipe 15 to the burners 40 within the fire-box raises the temperature therein to a very high degree, thereby intensifying the heat applied to the sections of the gas-generator and increasing their efficiency. The relief-valve 14 averts danger 45 from any abnormal pressure occurring in the gas-generator, and the petcock 13 serves to draw off such water as may be condensed from any residual unconverted steam.

While I have shown but one cylinder 4, I 50 may in some cases employ two or more, the steam from both either entering the gas-generator through pipe 6 or the second being connected to gas-generator section 9 only, in which case the connection between genera- 55 tors sections 8 9 may be omitted and the gas taken directly from the top pipe of each.

In some cases I may omit pressure-reducing valve 3, depending merely on control-valve 2 and the expansion in condenser 4 to reduce 60 the pressure of the steam to any desired extent.

The air-diffusing pan is an important adjunct of the gas-generator, it being important that the temperature in the fire-chamber be kept uniformly high to secure satisfactory 70 conversion of the steam into gas. The perforated plates 23 prevent any sudden inrush of cold air, which would otherwise lower the temperature, when the ash-pit door is opened.

What I claim is—

1. An apparatus for utilizing steam, comprising means for suddenly expanding the steam to a larger volume and separating it, without material condensation, from any water held in suspension, means for heating the 80 steam to a high temperature, and means for burning the gaseous products thereof in conjunction with other fuel, as set forth.

2. An apparatus for utilizing steam, comprising means for suddenly expanding the 85 steam and thereby reducing its pressure before it has had an opportunity to absorb water of condensation, and for separating from the steam the watery vapor therein without material condensation of the steam, means 90 for immediately superheating the steam to a high temperature, and means for introducing the resultant gaseous products thereof into a zone of combustion, as set forth.

3. An apparatus for utilizing steam, comprising a steam expansion and radiation chamber, means for drawing off the precipitated water from this chamber, a conduit connected to receive the dry lower-pressure steam from said chamber, means for heating 100 said conduit, and means for burning the gaseous products delivered from said conduit in conjunction with other fuel, as set forth.

4. An apparatus for utilizing steam, comprising a steam expansion and radiation 105 chamber, means for drawing off the precipitated water from this chamber, a conduit connected to receive the dry lower-pressure steam from said chamber, means for heating said conduit, means for burning a portion of 110 the resulting gaseous products in conjunction with other fuel, and means for using the remaining portion to digest solid substances, as set forth.

5. An apparatus for utilizing steam, comprising means for suddenly expanding the steam to a larger volume and separating it, without material condensation, from any water held in suspension, means for heating the steam to a high temperature, a fire-box having a grate and means for passing a diffused current of air through the grate, and means for injecting the gaseous products of the steam into said fire-box and there burning them in conjunction with other fuel, as set 125 forth.

In testimony whereof I have affixed my signature in presence of two witnesses.

LINUS PORTER BURROWS.
